United States Patent Office.

GEORGE W. YOUNG, OF ST. LOUIS, MISSOURI.

Design No. 4,612, dated January 24, 1871.

DESIGN FOR A FENCE-CAP.

The Schedule referred to in these Letters Patent and making part of the same.

I, GEORGE W. YOUNG, of the city and county of St. Louis and State of Missouri, have invented a certain new and useful Design for a Fence-Cap, of which the following is a specification.

The cap is made in sections of a foot, more or less, in length, and is intended for attachment to the top of a fence to prevent persons or dogs from climbing over, or cattle or horses from pressing upon the top of the fence. It is intended chiefly for board fences having a straight top.

The drawing represents one section in isometric perspective.

a is a bar having a flat under side to lie upon the top of the fence, and the edges of the bar *a* are

turned down in two flanges, *b*, to give a side hold on the fence.

c are a number of points, extending upward, and represented in echelon.

These points may be placed at a greater or lesser distance, and may vary in size.

The sections are attached to the fence by nails or screws passing through the bar *a* or flanges *b*.

I claim—

The design for a fence-cap, substantially as above set forth.
